UNITED STATES PATENT OFFICE.

JAMES H. SMITH, OF ROCHESTER, NEW YORK, ASSIGNOR TO J. HUNGERFORD SMITH COMPANY, OF ROCHESTER, NEW YORK, A CORPORATION OF NEW YORK.

ASSORTING-MACHINE.

1,179,570.

Specification of Letters Patent.

Patented Apr. 18, 1916.

Application filed October 20, 1913. Serial No. 796,105.

To all whom it may concern:

Be it known that I, JAMES H. SMITH, of Rochester, in the county of Monroe and State of New York, have invented certain new and useful Improvements in Assorting Machines; and I do hereby declare the following to be a full, clear, and exact description of the same, reference being had to the accompanying drawings, forming a part 10 of this specification, and to the reference numerals marked thereon.

The present invention relates to assorting apparatus and while having other and more general fields of usefulness, is well adapted 15 for such assorting as is involved in separating unstemmed or only partially stemmed portions of fruit, such as cherries, from the stemmed portions with which they are commingled. In the usual manner of stemming 20 cherries, as they are prepared for market, a certain small proportion are left either partly or wholly unstemmed, and the prime object of my invention is to provide a mechanism adapted to handle the cherries rapidly 25 and to separate automatically and with certainty the unstemmed ones from the main mass that are stemmed. To this end I provide a moving carrier shown as a large 30 drum, presenting a sloping surface at a cherry receiving point adapted to permit free rolling cherries—*i. e.* those that are properly stemmed, to roll downward to one 35 delivery point, the drum carrier having a slow movement moving the cherries in a direction opposite to that in which they tend 40 to roll from the receiving point, whereby those cherries which are non free rolling—*i. e.* which have attached stem portions, are carried by the movement of the carrier up- 45 ward until in the drum form shown they pass over the top and are discharged down on the other side at a separate delivery point. It is to be observed that in this assorting operation, I take advantage of the 50 free rolling capacity of the articles shown as cherries, when they are stemmed, and that the invention is thus adapted to assort various commodities wherein free rolling specimens are to be separated from those 55 that are non free-rolling, by reason of stems, projections or roughness.

The above and other specific objects of the invention will be better understood from the following detailed description taken in 55 connection with the accompanying drawings

and will be thereafter pointed out in the appended claims.

Referring to the drawings: Figure 1 is a side elevation of a machine wherein my invention is embodied; Fig. 2 is a plan view 60 thereof; Fig. 3 is a longitudinal, vertical section; Fig. 4 is an enlarged detail section on line 4—4 of Fig. 3; Fig. 5 is an enlarged detail section on line 5—5 of Fig. 3, and Fig. 6 is a detail side elevation of a chute located 65 between the delivery device and receiving drum.

Similar reference numerals throughout the several figures indicate the same parts.

Upon a suitable framework 10 I mount a 70 chute 11 or like source from which the cherries are fed. At the lower delivery end of this chute I journal a roll 12 having a plurality of lengthwise rows, shown as two, of cherry receiving pockets 13 therein, the roll 75 being mounted in close juxtaposition to the delivery end of the chute so that the cherries are automatically delivered by gravity into said pockets, as they come opposite the end of the chute. 80

Beneath the roll 12 and with its axis 14 somewhat in front of the axis of the roll, I mount for rotation a large drum 15, having a series of V-shaped grooves 16 extending around its circumference, these grooves being in vertical alinement with the several cherry receiving pockets 13 of the roll 12 respectively, and of a size so that the cherries are adapted to settle down thereinto some little distance, as best seen in Fig. 4. 90 These grooves receive the cherries and hold them in separated lines so that they do not interfere or tend to clog up in rolling on the drum.

In use, the roll 12 is rotated to intermittently deliver the cherries from the chute 11 into the grooves 16 and the drum 15 is rotated in the direction shown by the arrow in Fig. 3, quite slowly, with the result that as the cherries are deposited into the grooves 100 16, some little distance back of the top thereof owing to the rearward mounting of the roll 12, the stemmed cherries will roll backward down the drum 15 as indicated at α , faster than they are moved forward by 105 the drum 15 finally dropping into a receptacle 17 in position to receive the same at the back of the drum. The unstemmed or only partially stemmed cherries, however, have their rotation prevented or interfered with 110

by their projecting stems and so are moved forward by the rotating drum as seen at *b*, so that they are ultimately discharged into a receptacle 18 provided therefor at the front of the drum. The free rolling cherries are limited strictly to a rotating movement upon the drum by means of the shape of the groove 16, the sloping sides of which preferably meet at an acute angle whereby the 10 opposing surfaces of the groove walls form a two-point support contacting with the cherries only upon opposite sides of the same, thus reducing to a minimum the frictional resistance offered by the walls of the 15 groove in supporting the cherries. In this way sidewise or shifting movement of the articles within the grooves is obviated, which, if not overcome would tend to retard the free rolling movement of the bodies upon 20 the drum. The pockets in the roll 12 are so constructed as to deliver only one cherry at a time to each of the grooves 16 and one row of pockets is so positioned with respect to the other that the cherries delivered by 25 the first will be moved to the opposite sides of the drum before the next row of pockets makes its delivery, thereby obviating the mixing of the two classes of articles in the same groove at the same time.

30 As shown, driving impulse is imparted to the drum from a band wheel 19 and from thence to the roller 12 by a band connection 20. It is, of course, to be understood that the proper rate of rotation of the drum 15 35 to attain the described result, may be easily determined by trial and observation.

If desired there may be employed a delivery chute or slide located between the roll 12 and the drum 15, as shown particularly 40 in Fig. 6, the purpose of which is to receive the articles from the pockets in the roll 12, and direct them rearwardly relatively to the direction of rotation of the drum 15. The inclined chute or slide is indicated by *6*^a in 45 Fig. 6, and its lower or discharge end which lies adjacent to the periphery of the drum 15 is normally closed by the gate *b* pivoted at *c* provided with the operating arm *d* which coöperates with the cam *e* fixed to the 50 axis of the roll 12, the surface of said cam being so formed in respect to the pockets 13 of the roll 12 that the gate will be opened each time articles are deposited onto the slide *6*^a. This arrangement of the parts I 55 consider advantageous in some instances as it permits the speed of the roll 12 to be increased and prevents the cherries being deposited on the slide from being thrown by the centrifugal action imparted to them beyond the point on the receiving drum 15.

where they will, if free to roll, gravitate in the direction opposite to the movement of said drum. The impetus imparted to the articles by their movement down the inclined surface of the slide is checked by the gate *b* which when opened permits said articles to pass out and fall gently onto the drum 15.

While the described embodiment of the invention is deemed preferable on account of its extreme simplicity and effectiveness, I am aware that the invention can be embodied in various other specific forms without departing from the spirit thereof, and I therefore desire the present embodiment to be considered as illustrative and not restrictive and refer to the appended claims, rather than to the foregoing description to indicate the scope of the invention. I also desire it to be understood that the reference to cherries as the commodity being assorted is merely for illustrative purposes and that the invention is intended to include mechanism for analogous assorting operation where non-free rolling specimens are to be separated from relatively free rolling ones.

I claim as my invention:

1. An assorting machine comprising a rotatable drum having a series of grooves about its circumference formed by inclined meeting surfaces, a movable delivery roll spaced a substantial distance from the drum at the forward side thereof and provided with a series of individual article carrying pockets for intermittently delivering one article at a time to each of the grooves of the drum, and means for operating the delivery roll and the drum.

2. An assorting machine for separating two classes of articles, one being free-rolling and the other non-rolling, the machine comprising a rotatable drum having a series of grooves about its circumference formed by inclined meeting surfaces serving to form a two point support for said articles upon opposite sides of the same whereby the free-rolling bodies are limited to a rotating movement within the grooves in one direction while the non-rolling bodies are moved bodily in an opposite direction, a movable member for delivering said articles to the grooves intermittently, each succeeding delivery being effected after the previous delivery has moved away from the receiving point of the drum, and means for operating the movable delivery member and the drum.

JAMES H. SMITH.
